UNITED STATES PATENT OFFICE.

WILLIAM BRITTON GEARY, OF MEDICINE HAT, ALBERTA, CANADA.

INTERNAL-COMBUSTION ENGINE.

1,312,971.

Specification of Letters Patent.

Patented Aug. 12, 1919.

Application filed June 4, 1917. Serial No. 172,843.

To all whom it may concern:

Be it known that I, WILLIAM BRITTON GEARY, a subject of the King of Great Britain, and a resident of the town of Medicine Hat, in the Province of Alberta, and the Dominion of Canada, have invented certain new and useful Improvements in Internal-Combustion Engines, of which the following is a full description.

10 This invention relates to improvements in internal combustion engines of the four cycle type, and the objects of the invention are to dispense with the use of mechanically operated and spring controlled valves 15 and other renewable parts of a like nature which require constant attention and adjustment, and to permit of the fuel being fed to the cylinder and the products of combustion being discharged therefrom during the reciprocation of the piston and due to a rotary motion being imparted to the same during each cycle of the engine, whereby a port formed in the piston is alternately brought into alignment with inlet and exhaust ports 25 formed on diametrically opposite sides of the cylinder.

Further objects are to simplify the several parts and render the same easily accessible for inspection, to permit of the engine 30 being utilized for stationary, automobile or other purposes, and generally to adapt the several parts to better perform the functions required of them.

With these and other objects in view, the 35 invention consists essentially of the improved construction particularly described and set forth in the following specification and accompanying drawings forming part of the same.

40 In the drawings,

Figure 1 is a vertical section of an engine cylinder embodying the present invention.

Fig. 2 is a vertical section of an engine cylinder with the piston and the cylinder 45 head removed.

Fig. 3 is an elevation of the cylinder as seen when cut and developed into a rectangle.

Fig. 4 is a front elevation of the piston 50 with the cylinder head in section.

Fig. 5 is a perspective view of the worm wheel and curvilinear arms carried thereby designed to rotate the piston.

Fig. 6 is a plan view of the worm shown 55 in Fig. 5.

Fig. 7 is a perspective view of the piston rings designed to be utilized with the piston.

Fig. 8 is a transverse section of the piston on the line 2—2 of Fig. 4.

Fig. 9 is a detail of a cross section taken 60 through the ports.

Like characters of reference refer to like parts in the several figures.

Referring to the drawings, A represents an internal combustion engine comprising 65 the cylinder B having a water jacket 10 and provided on diametrically opposite sides with intake and exhaust ports 11 and 12 which communicate through conduits 15, 14 and 13 in the cylinder walls with passageways 9^a and 9 extending from the said conduits through the inner wall of the cylinder.

The conduits 13 and 14 are in communication with the exhaust port 12, while the conduit 15 communicates with the intake 75 port 11.

The conduits 13, 14 and 15 are angularly disposed, the first and last being considerably shorter than the intermediate one which extends practically the whole length 80 of the working stroke of the piston, and the openings 9^a and 9 are somewhat angularly disposed. I have found that an inclination of twenty-five degrees of the openings give 85 good results in practice.

The lower end of the cylinder is provided with a flange 16 designed to be engaged and secured to the crank casing 17 by means of screws 18 or the like, the upper end of the cylinder being provided with a cylinder 90 head 20 secured in position by studs 21 or the like. The cylinder head is provided with a flange 22 and is formed with double walls 23 and 24 providing a water jacket 95 25 to which cooling fluid is delivered through the inlet 26.

The cylinder head is also provided with a piston ring 27 which prevents any tendency of leakage of the motive fluid between the side walls of the cylinder head and the 100 sleeve 33 carried by the piston 28.

A spark plug 29 is threaded into the cylinder head 20 and the inner wall of the cylinder head is provided with a concave recess 30 into which the spark plug extends, the 105 said recess and clearance space between the head and piston giving adequate compression space for the motive fluid.

The piston 28 is quite unique and consists of a cylindrical body portion 31 having a 110 pair of curvilinear slots 32 arranged on diametrically opposite sides thereof and extending from the bottom face upwardly to near the top of the piston, while the upper

face of the piston is formed integral with the sleeve 33 designed to slidably engage between the wall 24 of the cylinder head 20 and the inner wall of the cylinder 10.

- 5 It will be noticed by reference to Fig. 1, that the wall 24 of the cylinder head is spaced from the inner wall of the cylinder leaving an annular passageway into which the sleeve 33 extends.
- 10 This sleeve is provided adjacent to its lower end with a port 34 located in the annular recess 35 in which the piston rings 36 are located, the said piston rings being designed to frictionally engage with the inner 15 wall of the cylinder 10 and prevent any leakage of combustible fluid, either in an upward or downward direction, while the piston ring 27 of the cylinder head engages with the inner wall or periphery of the 20 sleeve 33, and also obviates any tendency to leakage.

The piston 28 is connected to the crank shaft of the engine by the connecting rod 37 which terminates on the upper end in a 25 spherical enlargement 58 adapted to engage with the semi-spherical recess 39 in the lower face of the piston, this enlargement being held in position by a clamping member 40 which is secured to the piston by 30 means of screws 41 or the like.

It will thus be seen that the connecting rod 37 makes a ball and socket connection with the piston 28 so allowing the piston to be rotated in a horizontal plane during each 35 cycle of the engine.

The means which I preferably employ for rotating the piston consists of a worm wheel 42 which meshes with the worm 43 mounted on the spindle 44, the said spindle 40 being designed to be rotated from the crank shaft or any other part of the engine by any suitable mechanism.

To eliminate friction the worm wheel 42 is supported by the flanged ring 8 which 45 carries ball bearings 45 engaging the under face of the worm wheel, while the upper face of the wheel engages with the ball bearings 46 which engages with the ball race 7.

50 The flanged ring 8 and ball race 7 are secured to the flange 16 of the cylinder and the crank casing 17 of the recess 18.

The worm wheel is provided on diametrically opposite sides with a pair of curvilinear or arcuate arms 47 which are designed to make sliding engagement with the slots 32 formed in the piston 28, so that as rotary motion is transmitted to the worm wheel through the actuation of the worm 55 43, the said arms will engage with the lateral walls of the slots 32 and so rotate the piston 28.

The assembly of the several parts will be readily understood from the foregoing description.

When an engine equipped in this manner is in use, the spark plug 29 is connected to the usual magneto, batteries or the like, and during the reciprocation of the piston 28, rotation of the same takes place to control 70 the inlet of motive fluid and the exhaust of the products of combustion.

A complete four stroke cycle can be best illustrated by reference to Fig. 3.

Suppose, for instance, a charge of motive 75 fluid has been delivered to the engine, then during the first ninety degrees of rotation of the piston 28, that is to say on the in-stroke of the piston the charge is compressed. After being rotated through a 80 quarter of a turn, the piston has reached its innermost position and compression is completed.

Ignition now takes place, and the piston commences its outward stroke and when the 85 piston has reached about three quarter stroke, the port 34 in the sleeve 33 registers with the openings 9 in the conduit 13, which being in communication with the outlet port 12, permits the products of combustion to 90 exhaust.

The piston has now been rotated through one hundred and eighty degrees and has reached its outermost position. On the in- 95 ward motion of the piston the port 34 will register with the successive openings 9 in the conduit 14 which is a continuation of the conduit 13 and communicates with the exhaust port 12.

At the innermost end of the piston's third 100 stroke the exhaust is completed and the piston has been rotated through two hundred and seventy degrees.

On the beginning of the next outward stroke of the piston the port 34 registers 105 with the openings 9^a in the conduit 15 which communicates with the inlet port 11.

Motive fluid is thus fed to the cylinder and the fluid is compressed in the next inward stroke of the piston, the several phases being 110 repeated during each four stroke cycle.

By rotating the piston 28 during the reciprocation of the same the port 34 in the sleeve 33 follows a wave like path, so that it registers successively with the openings 115 9 and 9^a in the conduits 13, 14 and 15 respectively.

Cooling fluid is delivered to the jackets 10 and 25 during the working of the engine.

The rotation of the piston 28 is positive 120 since the arms 47 of the worm wheel engage with the end walls of the slots 32 and since the worm wheel is positively geared to the worm 43 which is driven from the engine, the timing of the registration of the port 34, 125 in the sleeve 33, with the openings 9 and 9^a, is readily accomplished so that the several phases of the cycle, namely, intake compression, ignition and exhaust take place in the required order to obtain the best results. 130

From this description it will be seen that I have invented an internal combustion engine in which all mechanically operated spring controlled valves are dispensed with, 5 the several parts being of an extremely simple nature, not liable to go out of repair.

As many changes could be made in the above description and many apparently widely different embodiments of my invention 10 within the scope of the claims constructed without departing from the spirit or scope thereof, it is intended that all matter contained in the accompanying specification and drawings shall be interpreted 15 as illustrative and not in a limited sense.

What I claim as my invention is:

In an internal combustion engine, a cylinder having conduits in the walls thereof, angularly disposed relatively to each other

with openings extending through the cylinder walls, said conduits being substantially continuous and Z-shaped in aspect with the intermediate conduit longer than the others, a piston reciprocating in the cylinder having a sleeve provided with a port 20 and means for rotating the piston to cause the port in the sleeve to register with the openings from the conduits, the said means consisting of a pair of arms engaging the piston, and means controlling the actuation 25 of the said arms.

In witness whereof I have hereunto set my hand in the presence of two witnesses.

WILLIAM BRITTON GEARY.
